Des. 181,449

Patented Nov. 19, 1957

181,449

LAWN TRIMMER

Victor N. Albertson, Rueben E. Paulson, and
Frederick C. Nielsen, Minneapolis, Minn.

Application July 2, 1956, Serial No. 42,113

Term of patent 3½ years

(Cl. D40—1)

Fig. 1 is a view in perspective of a lawn trimmer showing our new design, with a fragmental portion of a handle shown in broken lines for illustrative purposes only;

Fig. 2 is a view in top plan;

Fig. 3 is a view in side elevation; and

Fig. 4 is a view in bottom plan.

We claim:

The ornamental design for a lawn trimmer, as shown and described.
